[57] CLAIM

The ornamental design for an electric shaver, substantially as shown and described.

DESCRIPTION

FIG. 1 is a front elevational view of an electric shaver showing our new design with the protective casing removed;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a sectional view taken along line 9—9 in FIG. 1, internal mechanisms being omitted for ease of illustration;

FIG. 8 is a perspective view thereof;

FIG. 9 is a front elevational view of the shaver with the protective casing mounted;

FIG. 10 is a rear elevational view thereof;

FIG. 11 is a top plan view thereof;

FIG. 12 is a bottom plan view thereof;

FIG. 13 is a left side elevational view thereof;

FIG. 14 is a right side elevational view thereof;

FIG. 15 is a sectional view taken along the line A¹—A¹ in FIG. 9, internal mechanisms being omitted for ease of illustration; and

FIG. 16 is a perspective view thereof.
